Application September 30, 1940, Serial No. 95,520

Term of patent 7 years

To all whom it may concern:

Be it known that I, Edward S. Preston, a citizen of the United States, residing at Hinsdale, Du Page County, Illinois, have invented a new, original, and ornamental Design for a Washing Machine, of which the following is a specification, reference being had to the accompanying drawing forming a part thereof.

Figure 1 is a view in vertical elevation of a washing machine embodying my design;

Figure 2 is a top plan view of the design shown in Figure 1; and

Figure 3 is a fragmentary elevational view similar to Figure 1 with a portion of the cover and tub broken away to more clearly illustrate the features of the cover design.

The dominant features of my design reside in the portions illustrated in solid lines.

I claim:

The ornamental design for a washing machine, substantially as shown and described.

EDWARD S. PRESTON.
